US00D990103S

(12) United States Design Patent (10) Patent No.: US D990,103 S
Mendlar (45) Date of Patent: * Jun. 27, 2023

(54) SHOE

(71) Applicant: adidas AG, Herzogenaurach (DE)

(72) Inventor: Rainer Mendlar, Fuerth (DE)

(73) Assignee: adidas AG, Herzogenaurach (DE)

() Term: 15 Years

(21) Appl. No.: 29/857,595

(22) Filed: Oct. 24, 2022

Related U.S. Application Data

(63) Continuation of application No. 29/778,715, filed on Apr. 14, 2021, now Pat. No. Des. 967,621, which is (Continued)
